DESIGN FOR A PICTURE FRAME

Charles Raab, Chicago, Ill.

Application February 6, 1933. Serial No. 47,122

Term of patent 7 years

To all whom it may concern:

Be it known that I, CHARLES RAAB, a citizen of the United States, residing at Chicago, in the county of Cook and State of Illinois, have invented a new, original, and ornamental Design for a Picture Frame, of which the following is a specification, reference being had to the accompanying drawing forming part thereof.

Fig. 1 is a front view, and Fig. 2 is a side view, of a picture frame, showing my new design.

I claim:

The ornamental design for a picture frame, as shown.

CHARLES RAAB.
